UNITED STATES PATENT OFFICE.

GRANVILLE A. HUMASON AND JULIUS A. BURTSCHEL, OF HOUSTON, TEXAS.

CASING SPEAR.

Application filed August 16, 1920. Serial No. 404,021.

To all whom it may concern:

Be it known that we, GRANVILLE A. HUMASON and JULIUS A. BURTSCHEL, citizens of the United States, residing at Houston, Harris County, Texas, have invented a certain new and useful Improvement in Casting Spears, of which the following is a full, clear, and exact description, such as will enable others skilled in the art to which it applies to make and use the same.

Our invention pertains to an improvement in casing spears to be used in fishing operations in well drilling where it becomes necessary to withdraw pipe from the well.

In deep well drilling it sometimes occurs that due to accident or otherwise, the drill stem of pipe becomes broken off in the well and it then becomes necessary to insert a spear downwardly in the well to grip the upper end of the piece of broken off pipe and withdraw the same from the well. Or in some cases when a well is abandoned, or for other reason it becomes necessary to withdraw the casing from the well, a casing spear is inserted downwardly inside the casing and with such a tool the casing is pulled from the well. The usual difficulty with fishing tools used in withdrawing casing in this manner is that when they are once gripped upon the casing it is not easy, and is often impossible, to release the tool from the casing when it is found that the casing is so anchored or cemented in the well that it can not be withdrawn.

An object of our invention is to provide a casing spear which may be readily expanded into contact with the pipe in fishing operations, and which, at the same time, may be readily released when it is desired to withdraw the same from the pipe.

Another object is to provide a releasing means upon a fishing tool which may be operated to release the tool by the simple rotation of the mandrel upon which the gripping means is mounted.

Referring to the drawings forming a part of this specification, and wherein like numerals of reference are applied to like parts through the several views, Fig. 1 is a central longitudinal section through our improved device showing the same fitted within a length of pipe; Fig. 2 is a broken view thereof showing the releasing means in a different position, Fig. 3 is a transverse section taken on the plane 3-3 of Fig. 1; Fig. 4 is a side elevation of our releasing

collar, and Fig. 5 is a transverse section through a clamping means showing a slightly different embodiment thereof.

In the drawing we have shown a length 60 of casing or pipe 1 with our improved fishing tool therein. The said tool consists of a mandrel 2 having the upper portion thereof tapered upwardly to provide a slightly conical seat 3 for a clamping collar 4. The upper end of the mandrel is threaded at 5 for attachment to a drill collar 6, acting as a coupling to connect the tool to the drill stem to which it is attached. The lower end of the coupling 6 is provided with 70 an upwardly tapered recess 7, the purpose of which will later appear.

The lower portion of the mandrel 2 is cylindrical in shape and threaded at 23 to receive a releasing collar 8 threaded thereon. 75 The mandrel is tubular in construction, having a central channel 9 therethrough for the passage of water or other flushing fluid. The lower end of the mandrel is threaded interiorly at 10 to receive the shank of a 80 bit or spear 11, which acts as a guide or agitator when necessary in the introducing of the spear into the casing. The clamping member 4 is provided with a central tapered passage therethrough adapted to seat upon 85 the tapered mandrel at 3. It has a beveled upper end 12 and a similarly lower beveled end 13, said ends being adapted to fit within the recesses 7 of the collar 6, and 14 of the releasing collar 8, respectively. The outer 90 surface of the clamping collar 4 is provided with teeth 15, said teeth being inclined upwardly so as to grip the pipe only on the upward movement thereof. The lower faces of the teeth are inclined downwardly 95 so as to allow the tool to be inserted into the well without catching upon the interior of the pipe. The collar 4 is split longitudinally at one point so as to allow the expansion of the said collar when it is forced 100 downwardly upon the tapered mandrel 2.

The releasing collar 8 is provided with the tapered recess 14 in the upper end thereof, as previously referred to, and has, on the outer face thereof, two opposite friction springs 16. These springs are flat leaf springs, each being fitted within a shallow recess 17 in the outer face of the collar, and are secured in said recesses by rivets or screws 18 at one end thereof. The other 110 end of the spring is free to move longitudinally and is inserted beneath an over-hang-

ing flange 19 to prevent the same from being thrown out of the recess. The central portion of the spring is bowed outwardly and may be corrugated longitudinally there-
5 of, so as to bear against the pipe, within which it is inserted, in such manner as to prevent rotation of the collar 8 when the mandrel is turned. The springs do not, however, as will be obvious, interfere with
10 the insertion of the spear downwardly within the pipe.

In the operation of our device the tool is inserted downwardly within the well and within the casing 1, which is to be gripped
15 thereby. When the proper point has been reached the spear is jerked upwardly. This motion will cause the teeth 15 of the clamp-
ing collar 4 to grip against the casing. The further upward movement of the tool will
20 draw the mandrel 2 upwardly within the clamp-
ing collar 4 and serve to expand the latter outwardly against the casing with such force as to grip it firmly. The further upward movement of the fishing tool will
25 serve to pull the casing upwardly along with the tool. If it is desired to release the clamp-
ing collar 4 from the casing thereafter the tool is lowered in the well, thus forcing the mandrel downwardly through the clamp-
ing collar until the collar 6 contacts with the
30 upper beveled end of the clamp-
ing collar. The mandrel 2 will then be rotated within the collar 8. The springs 16 will serve to prevent the rotation of the releasing collar
35 and the rotation of the mandrel therein will serve to screw the mandrel downwardly within the collar 8, thus in effect drawing the collar upwardly into contact with the lower beveled end 13 of the collar 4. The
40 collar 4 will thus be forced upwardly until the same is gripped between the coupling 6 and the releasing collar 8, as shown in Fig.
2. The further rotation of the mandrel will then tend to clamp the collar 4 between the
45 beveled ends 7 and 14 of the coupling 6 and releasing collar 8, respectively, and thus draw the collar 4 into contracted position, releasing it from the casing, and allow the tool to be withdrawn from the well.

50 In Fig. 5 we have shown the clamp-
ing collar 4' as being divided longitudinally into four sections. The mandrel 2' is formed with flat sides 20; having a dove-tailed mortise
55 21 therein. Each of the sections of the clamp-
ing collar 4 is provided with a dove-tailed tenon 22 fitting within the dove-tailed mortise 12, so as to allow a sliding move-
ment of the collar longitudinally of the mandrel. The sliding of the collar upon the
60 mandrel in this form will act, as will be apparent, to draw the collar inwardly as it moves up and to force it outwardly as it moves downwardly. The releasing collar 8 would not necessarily have to be beveled on its upper end in this modification as the

dove-tailed connections of the sections of the clamp-
ing collar 4 with the mandrel would act in itself to draw the said collar gradually into contracted position without the clamp-
ing effect of the releasing collar 70 and the coupling 6.

It will be obvious that this type of tool is strong and rugged in construction and positive in its action and that it will be cheap to manufacture and not liable to get out
75 of order or fail to operate at critical times. The advantages of such construction will be apparent without further description.

What we claim as new and desire to protect by Letters Patent is:

80 1. In a tool of the character described, a tapered mandrel, a clamp-
ing collar thereon, said collar being split longitudinally and provided with upwardly inclined teeth thereon, a releasing collar below said clamp-
ing collar, means to hold said releasing collar against rotation and means to draw
85 said releasing collar upwardly to release said clamp-
ing collar comprising a threaded connection between said mandrel and said clamp-
ing collar.

90 2. In a tool of the character described, a tapered mandrel, a clamp-
ing collar having beveled upper and lower ends thereon, a coupling above said clamp-
ing collar having a tapered recess therein, a releasing
95 collar below said clamp-
ing collar threaded unto said mandrel and having a tapered recess in the upper end thereof, and means to prevent rotation of said releasing collar
100 when said mandrel is rotated.

105 3. In a tool of the character described, a tapered mandrel, a clamp-
ing collar fitting thereon, said collar being split longitudinally and provided with teeth on the outer
110 face thereof, a threaded lower end on said mandrel, a releasing collar fitting on said threaded surface, means to prevent rotation of said releasing collar whereby said
releasing collar may be drawn upwardly by
115 the rotation of said mandrel.

120 4. In a tool of the character described, a tapered mandrel, an expanding collar fitted thereon, a coupling at the upper end of said mandrel having a tapered recess
125 therein, a releasing collar below said mandrel having a tapered upper recess therein, tapered upper and lower ends on said expanding collar, and means to draw said releasing collar upwardly so as to clamp said expanding collar between the same and said coupling, operable by the rotation of said mandrel.

130 5. In a tool of the character described, an upwardly tapered mandrel, a clamp-
ing collar fitting slidably on said mandrel whereby said collar may be moved downwardly and expanded, a releasing collar threaded to said mandrel below said clamp-
ing collar, and means to screw said releas-

ing collar upwardly on said mandrel against said clamping collar to cause said clamping collar to contract.

6. In a tool of the character described, a mandrel tapering upwardly, a split clamping collar thereon adapted to be expanded by the relative upward movement of said mandrel, a threaded portion on the lower end of said mandrel, a releasing collar on

said threaded portion adapted to be raised 10 upwardly by the rotation of said mandrel so as to release said clamping collar and means to prevent rotation of said releasing collar.

In testimony whereof, we hereunto affix our signatures, this 11th day of August, 15 A. D. 1920.

GRANVILLE A. HUMASON.
JULIUS A. BURTSCHEL.
